[57] CLAIM

The ornamental design for a magnetic card reader, as shown and described.

DESCRIPTION

FIG. 1 is a perspective view of a magnetic card reader of our new design;
 FIG. 2 is a front elevation of the magnetic card reader;
 FIG. 3 is a left side elevation of the card reader;
 FIG. 4 is a right side elevation of the subject card reader;
 FIG. 5 is a top plan view of the subject card reader; and
 FIG. 6 is a bottom plan view of the subject card reader. The mounting panel is shown in broken lines for illustrative purposes only.

FIG. 1

FIG. 2
